UNITED STATES PATENT OFFICE.

JOSEPH MIOTKE, OF MILWAUKEE, WISCONSIN.

FLOOR-SCRAPER.

No. 904,709.

Specification of Letters Patent.

Patented Nov. 24, 1908.

Application filed May 15, 1907, Serial No. 373,819. Renewed May 18, 1908. Serial No. 433,595.

To all whom it may concern:

Be it known that I, JOSEPH MIOTKE, of Milwaukee, Wisconsin, have invented a Floor-Scraper, of which the following is a specification.

This invention relates to scrapers or scraping-machines for floors, of the wheeled type, such machines being provided with wheels on which they run, with a long handle by which they are dragged over the floor in the active scraping direction and rolled in the opposite direction, said handles being ordinarily secured in a pivotal manner to the machine. In all such scrapers as hereinbefore devised, so far as I am aware, the force by which the scraping-blade is pressed against the floor depends directly upon the upward pull upon the handle. In the ordinary form of scraper the axis of the wheels forms the fulcrum of a two-armed lever, at one end of which is the scraping-blade and at the other the handle, so arranged that the upward movement of the handle is accompanied by a downward movement of the blade and vice versa. Such scrapers cannot be operated so as to maintain at all times a uniform pressure of the scraping-blade upon the floor, because the force of the upward pull (which is the vertical component of an oblique pull, the horizontal component of which is the force necessary to shave a shaving from the floor) necessarily varies according to the angle at which the handle is held and with the force necessary to cut a shaving, which in turn varies with the relative hardness of the wood. Such a scraper moreover requires considerable skill of manipulation to maintain even a moderately uniform action of the scraping-blade, and it presents the further great disadvantage that it requires a strong man to operate and is very wearisome and exhausting upon the back muscles, owing to the continual upward pull necessary to operate it. Moreover it has the further disadvantage that the blade cannot follow the unevennesses of the floor because the plane of the scraper-blade is regulated by the positions of the wheels, so that the scraping-blade does not always rest upon the floor along its entire length but sometimes only at one corner or end, and consequently cannot cut a uniform shaving the entire width of the blade.

It is my object to obviate these disadvantages and to produce a scraper which

even an unskilled person can operate with efficiency; which does not depend for the pressure of the scraping-blade upon the floor upon the amount of strength or direction of pull which is given to the handle by the operator; which is operated to scrape the floor without any vertical or upward pull upon the handle; and which is so devised that the blade will rest at all times upon the floor over its full length when in operation. I also aim to provide certain novel and useful subsidiary conveniences and auxiliary devices, the nature of which will appear hereinafter.

The main principle upon which my scraper rests is one which is absolutely novel to this class of devices; and it consists in so connecting the handle with the machine that a backward pull upon the handle, as in the active scraping direction, is accompanied by a shifting of the point of support of the scraper body toward the rear (that is away from the scraper-blade) whereby the actual weight of the scraper is divided between said point of support and the scraper-blade; whereas a push upon the handle, as in returning the scraper for a new cut, is accompanied by a shift of the point of support back again to a point practically under or in front of the center of gravity of the machine, whereby the latter is caused to tilt back and raise the scraping-blade from the floor. This function may be carried out in various ways, of which the most convenient is perhaps that herein shown, namely the provision of two separate rolling supports, one on each side of the center of gravity, with a lever connection between the machine and the handle whereby a rearward pull upon the latter acts to relatively depress the rear rolling-axis and raise the front rolling-axis, and a push upon said handle acts in the reverse manner.

Other features of my invention are a locking device whereby the machine may be locked in the raised position of the scraping-blade when not in use; a division of the machine into two separable parts of approximately equal weight, each of which is provided with its own means for lifting and carrying it, thereby rendering transportation easy; and such other constructions and combinations as will be hereinafter pointed out and specifically set forth in the claims.

For the better understanding of my invention I have hereinafter described two forms

in which the same may be carried out, these forms being respectively illustrated in the accompanying drawings.

In these drawings, Figure 1 is a side elevation of one form of scraper according to my invention, in its normal position. Fig. 2 is a similar view showing the scraper in the scraping position. Fig. 3 is a plan view of the scraper. Fig. 4 is a longitudinal section thereof, on a larger scale. Fig. 5 is a plan view of the body of the scraper, the weight and handle being removed. Fig. 6 is a transverse section through the scraper on the plane 6. Fig. 7 is a longitudinal section 15 through an alternative form of scraper according to my invention, in its normal position. Fig. 8 is a plan view thereof without the weight, and Fig. 9 is a side elevation of the same in the scraping position.

20 In these drawings every reference letter and numeral refers always to the same part.

Describing first the form of scraper shown on Sheet 1 of the drawings, the frame or body A as shown is of generally rectangular form and carries front and rear axles B and C, on which are mounted wheels b¹ and c¹ respectively. The axles B and C may or may not turn with the wheels, but in the present instance the wheels are mounted 25 loose thereon and the axles kept in position by split-pins b² and c² (Fig. 5). The rear wheels c¹ may in some cases be provided with rubber tires c³. The front axle B is mounted in holes in the frame as shown, but the rear axle is not fixedly connected with the same 30 but merely forms a rest or support therefor in the normal position of the scraper. The frame A is notched out on each side as shown at a¹, Fig. 4, whereby the axle C may move 35 up and down relative to the frame, or rather the frame moves up and down relative to the axle, and the upper ends of said notches a¹ rest upon the axle in the normal position of the frame. The axle B is mounted in 40 sockets in the rear end of a lever member D, which is pivoted upon the frame by means of an axle or shaft E¹ mounted in holes in the sides thereof. Said lever member D is provided with upstanding side-flanges d¹ 45 arranged to receive between them the handle E which may be secured thereto by any suitable means, such as screws d² passing through holes d³ in said flanges, and said handle E is shown as provided with hand-holds e¹ at the top; but any other suitable 50 form may be adopted, this being immaterial to my invention.

The front end of the scraper-frame A is made preferably with a heavy transverse member a² (see Fig. 4) which is faced off obliquely as shown, for the reception of the scraper-blade F, this latter having the usual turned or curved edge f¹ so formed that when pressed downwardly upon the floor 55 and the scraper is drawn backward it will

cut a shaving from the surface of the floor. The blade F is held in position by means of a plate G against the back thereof, which latter is in turn secured to the frame A by means of suitable capscrews g¹ entering holes a³ in the member a².

To give necessary or desirable weight upon the blade during action, especially for broad blades, it is desirable that the front end of the frame be weighted, and to this end I have provided a detachable weight H, which, as shown, fits on top of the front of the scraper-frame in such position that its center of gravity is substantially immediately over the axle B; but this precise position is not necessary to the operativeness of my invention. Said weight is secured in place by means of a bolt I, which passes through a hole formed in the center thereof and engages with a threaded hole a⁴ in a bolting lug a⁵ on the frame. The bolt I is provided also with a shoulder or nut i¹ (which is in effect the same as a shoulder), this latter reciprocating in a recess h¹ in the weight, said recess being made deep enough so that when the weight is removed from the machine and set down upon the floor the end of the bolt I retires into the recess h¹ and thereby the floor is not dented by the pressure of the end of the bolt I thereupon. At its upper end the bolt I is conveniently provided with a handle i², which serves not only for tightening the bolt I but also for carrying the weight H when removed from the machine.

At the rear side of the weight I is a locking device consisting of a pivoted dog or catch J swinging upon a pivot-pin j¹ said dog being of just the proper length to engage when dropped to its vertical position 105 with the cross-member d⁴ of the lever member D (which cross-member is disposed forward of the pivot E¹), and it consequently in this position prevents the rotation of the handle E and lever-member D and the tilting of the scraper-frame, as will be presently described. The dog J may be conveniently provided with a finger-piece j² for turning it in those designs in which it is inconvenient to reach the long limb of the 110 dog with the finger, and a pin j³ is set upon the side of the weight H to support the dog in a horizontal position when the scraper is in use.

The operation of the scraper is as shown in 120 Figs. 1 and 2, the former being the position in which the scraper normally rests and which it will assume when being pushed forward by a horizontal pressure upon the handle E, said pressure tending to rotate the 125 lever-member D in a left-hand direction. On the other hand, a backward pull upon the handle E tends to rotate the lever-member D in a right-hand direction, so that it assumes the position shown in Fig. 2, and 130

in dotted lines in Fig. 4. This raises the rear end of the frame A until the scraper-blade F rests upon the floor, and further until the wheels b^1 are raised completely off the floor, so that the weight is now supported entirely by the scraper-blade F at the front and by the wheels c^1 at the rear. It is to be observed that any slight variation in the position of the handle E or any variation in the amount of pull exerted thereupon, will have no sensible effect upon the pressure of the scraper-blade upon the floor, this latter depending solely upon the weight of the forward end of the frame; so that the action of the scraper-blade will be uniform, which is, so far as I know, not the case with any other scraper. Furthermore it is thus possible to bring the greater part of the entire weight of the machine upon the scraper-blade directly, the actual amount or proportion depending upon the relative distances from the center of gravity of the whole of the edge f^1 of the blade and the axle C respectively. The position which the floor K assumes relative to the machine when in operation is indicated by the dotted lines k^1 of Fig. 4. It is convenient to divide the weight of the machine about equally between the weight H and the remainder of the machine; and for convenience of transportation there may be provided a handle d^5 at the forward end of the lever member D, and the rear transverse member a^6 of the frame may be appropriately rounded off to form a second handle. The handle d^5 is so placed as when raised to lie approximately directly over the center of gravity when the frame is in horizontal position, and can thus carry the machine horizontally, while the handle a^6 is so disposed that the frame is carried vertically thereby. By dividing the weight equally between the member H and the remainder it is more easy to carry the machine with one member in each hand.

Referring now to the form of scraper shown on Sheet 2 of the drawings, there is shown a scraper-frame M supported by front and rear axles N and O, the former of which carries a pair of wheels n^1 rotatably mounted thereon, while the latter carries a single central wheel o^1 . The axles N and O are not mounted in fixed positions relative to the frame, but are slideable in oblique cam-slots m^1 and m^2 respectively. A lever-member P is pivoted on a pin Q in an intermediate position on the scraper-frame, said pin Q being mounted in a transverse member m^3 of the frame, which has an opening m^4 in the center to receive the end of the lever-member P as shown in Fig. 7. The lever-member P is connected to the axles N and O by means of links R and S which turn freely on the axles N and O and upon a pivot-pin T which passes through the member P; and said member P is also provided

with handle-flanges p^1 adapted for the attachment of a handle-bar as shown in the first form of scraper. The weight H and its connections are substantially the same as shown in the first form, with the exception of the bolt U having a slightly different form of collar u^1 and handle u^2 .

It is apparent from an inspection of the drawing that pushing upon the handle to move the scraper forwardly will cause it to assume the position shown in Fig. 7, while pulling upon it will turn the lever-member P into the position shown in Fig. 9, the scraper-frame being pressed forward with respect to the wheels, so that the axles N and O move to the rear ends of their respective slots m^1 and m^2 , whose obliquity is so directed as to throw the nose of the scraper downwardly until the scraper blade strikes the floor, and thereafter until the forward wheels n^1 are raised therefrom, thus bringing the entire weight of the front end of the apparatus upon the scraper-blade. A different form of locking-device for the apparatus is also shown in this form. Upon the rear transverse connecting-web m^5 of the frame is pivoted a locking-bar V upon a screw-stud v^1 , which is capped by a washer v^2 and nut v^3 upon the reduced end thereof, in such manner as to allow a certain amount of vertical play to the bar V. The bar V has a shoulder v^4 upon its lower face which rests upon the edge of the transverse member m^5 , that is upon the front or rear edge thereof according as said locking-bar is turned into the locked or unlocked position, the former of which is shown in dotted lines and the latter in full lines in Fig. 7. When in the locking position the end of the bar V lies against the back of the lever-member P and prevents its rotation.

It is to be observed that, while the front axle of my scraper requires substantially either two rollers or at least one of sufficient breadth to maintain the frame level against transverse oscillation, the support from the rear axle, on the contrary, should be only at or near the central axis, so as to permit of lateral oscillation sufficient to bring the scraper-blade into even contact with the floor along its entire edge. In the first form hereinabove described this is accomplished by placing the pivot-lugs of the member D close together and giving them a certain looseness; in the second form by providing but a single central roller. This, however, is to be understood as a desirable, but not essential feature of my scraper. It is also to be observed that my scraper provides special means for limiting the depth of the cut where that end is desired. While, under ordinary circumstances of operation, the full regular depth of the cut, corresponding to the amount of the weight, is desired, under certain circumstances it is desired to take a

lighter cut and this can be readily done by 5 pressing downward slightly upon the handle at its limiting position, which acts to turn the scraper as a whole in a clock-wise direction (as seen in the drawings), or rather to bring pressure to that end so as to take off a certain part of the effective weight upon the scraper blade, depending upon the amount of pressure. With a little practice 10 the operator readily learns to operate the apparatus so as to get a lighter or heavier cut exactly as may be desired.

The principles hereinabove described may be carried out in a variety of other forms 15 and ways, the two forms above given being cited merely as examples of the principle involved, and it will be understood therefore that I do not consider myself limited to the aforesaid forms, nor otherwise except as may 20 be apparent from a reasonable construction of my claims.

Having thus described my invention what I claim as new and desire to secure by Letters Patent is:

25 1. The combination of a frame, means for attaching a scraping-blade at the front end thereof, said blade being adapted to scrape when drawn rearwardly, a rolling support for said frame, said support being in advance of the scraping-blade in the scraping movement of the tool and during its engagement, and means for shifting the point of application of said frame upon said support toward and from said scraping-blade.

35 2. The combination of a frame, means for attaching a scraping-blade upon the front end of said frame, said blade being adapted to scrape when drawn rearwardly, a rolling support for said frame, said support being in advance of the scraping-blade in the scraping movement of the tool and during its engagement, and means for shifting the resting point of said frame upon said support in a longitudinal direction.

45 3. The combination of a frame, means for attaching a scraping-blade to the front end thereof, said blade being adapted to scrape when drawn rearwardly a pair of rolling supports for said frame at different distances from and on the same side of said scraping-blade, and means for altering the proportion of weight of said frame borne by the respective supports.

4. The combination of a frame, means for 55 attaching a scraping-blade to the end of said frame, a rolling support for said frame, a lever, said support being in advance of the scraping-blade in the scraping movement of the tool and during its engagement and 60 means operated by said lever for shifting the effective point of application of said support to said frame.

5. The combination of a frame, means for 65 attaching a scraping-blade to one end of said frame, a rolling support for said frame,

said support being in advance of the scraping-blade in the scraping movement of the tool and during its engagement, a handle pivoted to said frame and acting as a lever, and means actuated by said handle when turned upon its pivot to shift the point of application of said rolling support to said frame toward and from said scraper-blade. 70

6. The combination of a frame, means for attaching a scraper-blade to one end of said frame, a pair of rolling supports at different distances from said scraper-blade, a lever, and means actuated by said lever for varying the proportion of the weight of said frame carried by the respective supports. 75

7. The combination of a frame, means for attaching a scraper-blade to one end of said frame, a pair of rolling supports for said frame at different distances from said scraper-blade, the axis of said supports being shiftable with respect to said frame, said supports being in advance of the scraping-blade in the scraping movement of the tool and during its engagement, and means for raising and lowering one of said supports with respect to the other. 85

8. The combination of a frame, means for attaching a scraper-blade to one end of said frame, a pair of rolling supports at different distances from said scraper-blade, said supports being in advance of the scraping-blade in the scraping movement of the tool and during its engagement, the axis of rotation of said supports being substantially 95 transverse to said frame, and means for transferring part or all of the weight supported by one of said supports to said scraper-blade and the other support. 100

9. The combination of a frame, means for attaching a scraper-blade to one end of said frame, a pair of rolling supports for said frame at different distances from said scraper-blade and having their axes of rotation substantially transverse to said frame, 110 said supports being in advance of the scraping-blade in the scraping movement of the tool and during its engagement, a handle connected with said frame and adapted to move it backward and forward to operate the machine, and means actuated by said handle for varying the proportion of weight of said frame carried by the respective supports. 115

10. The combination with a frame and means for attaching a scraper blade to one end of said frame, of a rolling support for said frame behind said scraper blade and having its axis substantially transverse to said frame, a second rolling support having 120 its axis of rotation likewise transverse to said frame and at the rear thereof, a handle attached to said frame, and means connecting said handle with said supports whereby 125 upon the forward movement said handle 130

- causes said rear support to be raised relative to said front support, and upon the reverse motion said handle causes said rear support to be depressed relative to said front support whereby said blade is brought in contact with the floor-surface.
11. In a scraper, the combination of a frame, means for attaching a scraper-blade to one end of said frame, a pair of transverse roller-supports behind said blade and at different distances from said scraper blade, a handle pivoted to said frame and acting as a lever, and means connecting said handle with said supports whereby a pull upon said handle causes the weight carried by said front support to be fully or partly removed therefrom, and a push upon said handle causes it to be restored thereto.
12. In a scraper, the combination of a frame, means for attaching a scraper-blade at one end of said frame, a pair of transverse roller-supports behind and at different distances from said scraper-blade, a handle, and means connecting said handle with said supports whereby a rearward pull upon said handle causes the forward support to be raised from the ground thus causing the apparatus to rest upon said scraper-blade and the rear support.
13. In a scraper, the combination of a frame, means for attaching a scraper-blade at one end of said frame, a pair of rolling supports behind and at different distances from said scraper-blade, a handle connected with said frame, the center of gravity of the whole lying between said wheel-supports whereby the apparatus normally rolls thereon and said scraper-blade is supported at a distance from the floor, and means actuated by a pull upon said handle for increasing the distance between said frame and the rear support whereby it is tilted forwardly until the front support ceases to sustain the frame and the latter rests upon the scraper blade.
14. In a scraper, the combination of a frame, means for attaching a scraper-blade to one end of said frame, a rolling support upon said frame behind said blade and having a transverse axis, a lever-member pivoted to said frame, a second rolling support having a transverse axis to the rear of the first and mounted on said lever, and a handle secured to said lever-member and acting by a pull thereon to raise the rear end of said frame relative to said rear support whereby the front end thereof is made to rest upon said scraper-blade.
15. In a scraper, the combination of a frame, means for attaching a scraper-blade to one end thereof, one or more rolling supports for said frame, a weight detachably mounted upon said frame, and a bolt passing through the center of said weight and engaging with a threaded socket in said frame; said bolt having permanent slidable connec-
- tion with said weight and a handle at its upper end whereby it may be turned to secure and release said weight and whereby said weight is lifted and transported.
16. In a scraper, the combination with a frame and means for attaching a scraper-blade to one end thereof, rollers mounted near the front of said frame, a lever-member pivoted on said frame, one or more rollers pivoted on said lever-member to the rear of the pivot of the latter upon the frame, and a handle connected with said lever-member.
17. In a scraper, the combination with a frame and means for attaching a scraper-blade to one end thereof, rollers mounted near the front of said frame, a lever-member pivoted on said frame, one or more rollers pivoted on said lever-member to the rear of the pivot of the latter upon the frame, and a handle formed on said lever member forward of the pivot thereof whereby said frame is lifted and transported.
18. In a scraper, the combination with a frame and means for attaching a scraper-blade at one end thereof, of rolling supports for said frame arranged to support said scraper-blade out of contact with the floor, a handle attached to said frame and having means for tilting said frame whereby said scraper-blade is brought in contact with the floor, and a locking-device adapted to prevent said scraper-blade from being brought into contact with the floor.
19. In a scraper, the combination with a frame and means for attaching a scraper-blade at one end thereof, of rolling supports for said frame arranged to support said scraper-blade out of contact with the floor, a handle attached to said frame and having means for tilting said frame whereby said scraper-blade is brought in contact with the floor, and a locking-device adapted to prevent said frame from being tilted.
20. In a scraper, the combination with a frame and means for attaching a scraper-blade to one end thereof, of rolling supports for said frame adapted to roll on two transverse axes on opposite sides of the center of gravity of said frame, a lever-member adapted to raise the front support relative to the rear support whereby the weight is removed from the former, and a locking-device adapted to prevent the aforesaid action of said lever member.
21. In a scraper, the combination with a frame and means for attaching a scraper-blade to one end thereof, of rolling supports for said frame adapted to roll on two transverse axes on opposite sides of the center of gravity of said frame, a lever-member adapted to raise the front support relative to the rear support whereby the weight is removed from the former, and a pivoted locking-bar adapted when placed in the locking position to block the movement of

6
said lever and prevent the operative action of the scraper.

22. In a scraper, the combination with a frame and means for attaching a scraper-blade at one end thereof, of an axle transverse to said frame, a pair of rollers mounted upon said axle, a detachable weight mounted over front end of said frame, a handle-lever pivoted upon said frame, one or more rear rollers rotatably mounted upon said lever-member at a point to the rear of the pivot thereof, and a pivoted lock-bar adapted when in locked position to project into the path of said lever-member and prevent the same from being rotated to depress said rear roller or rollers relative to the frame.

23. A floor-scraper comprising, in combination, a frame having means for attaching

a scraper-blade at one end thereof, roller supports for said frame, said supports being in advance of the scraping-blade in the scraping movement of the tool and during its engagement, a lever-handle connected with said frame and acting to shift said roller-supports in such manner as to bring the scraping edge of said blade in contact with the floor surface, and means limiting the continuous movement of said lever-handle whereby the pressure thereon beyond said limiting position tends to raise said blade from the floor surface.

In testimony whereof, I have hereunto set my hand in the presence of two witnesses.

JOSEPH MIOTKE.

In presence of—

MINNIE SCHIENBERN,
GEORGE W. COLLS.
